Inventor

Adam Andreck

Patented Sept. 22, 1925.

UNITED STATES PATENT OFFICE.

ADAM ANDRECK, OF TORONTO, ONTARIO, CANADA.

CUE HOLDER.

Application filed June 5, 1925. Serial No. 35,147.

To all whom it may concern:

Be it known that I, ADAM ANDRECK, a citizen of Poland, and resident of Toronto, in the Province of Ontario and Dominion of Canada, have invented certain new and useful Cue Holders, of which the following is a specification.

This invention relates to improvements in cue holders, particularly to holders for billiard cues and the like, and it is the principal object of the invention to provide a holder of this character with means of novel and improved construction for holding the holding members in open position to receive the cue, and to open these members positively and automatically upon the removal of the cue from said holding members.

Another object of the invention is the provision of novel and improved gripping members for the cue.

A further object of the invention is the provision of a cue holder of novel and improved construction of a simple and inexpensive nature yet efficiently operating to hold and release a cue.

These and other objects and advantages of my invention will become more fully known as the description thereof proceeds, and will then more specifically be defined in the appended claims.

In the accompanying drawing, forming a material part of this disclosure:

Fig. 1 is a front elevation of the holder attached to a support with its gripping members in their open, cue releasing position, constructed according to the present invention.

Fig. 2 is a sectional side elevation thereof, on line 2—2 of Figure 1.

Fig. 3 is a section on line 3—3 of Figure 1.

Figure 4 is a front elevation of the cue holder with the gripping members in their closed, cue holding position.

The cue holder comprises a base plate 10 of metal or other suitable material adapted to be attached to a wall or like supporting surface by means of any desired fastening means passing through the corner holes 11 in said plate.

On said base plate is held in position by means of a pin or screw 12 the body part of the holder designated 13 and provided with a longitudinally extending slot 14 through which said screw extends into the base plate.

This body of the holder has the form of a

plate which is wider at its lower end and narrower at its top having beveled edges.

At the lower end of the slot 14 the material of the body plate 13 is cut to form an opening 15 and the cut out part, still connected to the body along its upper edge is bent out of the plane of the body part at a right angle thereto to form an abutment plate 16 or the like.

The screw 12 projects out of the plane of the body plate in front thereof and carries a collar 17 engaging the body plate for firmly holding the same against the base-plate.

Two operating arms 18, 19 have their inner looped ends guided around the screw below or behind the head thereof, while their outer ends are formed into hooks adapted to engage holes in the outer ends of the gripping members 20 and 21 having substantially the form of a question mark with their inner curved ends guided about the side bars of a bail 22 the inner ends of which are secured to the body plate near the lower edge thereof. The extreme outer ends of the gripping members which are curved, are made integral with or attached to plate-members or brackets 23, 24 movably mounted on the side bars of the bail by passing the same through holes in the angularly bent outer and inner ends of said brackets.

The inner, oppositely disposed faces of the gripping members are cushioned by means of a rubber mounting 25 extending to nearly the outer ends of said members which are passed through these rubber mountings.

A cam 26 is pivotally secured intermediate its ends and near the inner edge thereof by means of a pin 27 to the body plate to one side of its longitudinal slot, and said cam plate has a lower end substantially cut out on the arc of a circle as shown at 28 to engage over the rounded shank of the screw above the collar 17. The pin 27 is adapted to be displaced within an arcuate slot 29 near the upper edge of the cam plate extending from near its inner edge to near the outer edge thereof.

The device operates as follows:

Assuming the parts are in their position shown in Figure 1 with the gripping members held apart and the cam engaging screw 12 with its cut out lower end 28, if it is now

100

115

desired to place a cue into the holder, the same is with its upper end introduced between the gripping members into engagement with the abutment plate 16 which will be lifted by the cue together with body plate 13 and the cam plate attached thereto which will thus be disengaged from screw 12 and will on account of its weight and the fact that its pin 27 is displaced in slot 29, assume the position shown in Figure 2 in which the gripping members by the weight of the cue will firmly engage and hold the same assisted by the brackets 23, 24. If it is now desired to release the cue, the same is lifted, until the cam engages again under its own weight and on account of the displacement of its pivot pin in arcuate slot 29, the screw 12 so that the cue may now be drawn out of the holder, as in this position of the gripping members and their operating arms the latter will spread the grippers as shown in Figure 1.

It will be understood that I have shown and described as an example the preferred form of my device only, and that the same can be subjected to many changes in its construction such as fall within the scope of the appended claims without departure from the present invention which moreover constitutes a substantial improvement over the known devices by the construction of the cam plate adapted to make the action thereof as positive as possible on account of the recess on the arc of a circle at its lower end and the arcuate slot allowing a displacement of the cam plate by the engagement of its pivot pin in said slot and its displacement therein. Furthermore, the movably mounted brackets 23, 24 greatly facilitating the introduction and holding of the cue in the holder between the gripping members thereof which are mounted with a rubber mounting over their entire face engaging the cue without danger of injuring its polished surface.

Having thus described my invention, what I claim as new, and desire to secure by Letters Patent is:

1. In a cue holder of the class described a means for locking the gripping members of the holder in their open position, said

means comprising a cam having a curved lower end and an arcuate slot in its upper end, a pivot pin for said cam adapted to travel in said arcuate slot to lock and unlock said members.

2. In a cue holder comprising a pair of gripping members for engaging a cue, a rubber mounting on said members, a movable, longitudinally slotted body plate, a bail on said plate, a pair of brackets movably mounted on the lateral branches of said bail to which the inner ends of said members are attached, a means for normally holding said gripping members in their open position, a means for locking said members in this open position, and an abutment plate for a cue adapted to unlock said gripping members upon its engagement by a cue to allow a support of the same in said holder by its own weight.

3. In a cue holder of the class described, a metal base plate adapted to be secured to a support, a movable, longitudinally slotted body plate, a screw passing through the slot in said body plate into said base plate and projecting in front of the same, an abutment plate formed integrally with said body plate, a pair of gripping-members having substantially the form of question marks, a pair of operating arms secured at their outer ends to the outer ends of said gripping members, and guided with their looped inner ends about said screw, a rubber mounting for said gripping members, a bail attached to said body plate under said abutment, a pair of brackets movably attached to the lateral branches of said brackets, and having the inner ends of said gripping members attached thereto, and a cam member having a lower curved recessed end adapted to engage said screw, and an upper arcuate slot, a pivot pin for said cam member adapted to travel in said arcuate slot for allowing a lowering of said cam under its own weight when disengaged from said screw by a cue engaging said abutment to be gripped between said gripping members and suspended in the holder under its own weight.

Signed at Toronto, in the Province of Ontario, Dominion of Canada.

ADAM ANDRECK.
